CLAIM

We claim the ornamental design for an accessory for aerosol generator, as shown and described.

DESCRIPTION

FIG. 1 is a top front perspective view of an accessory for aerosol generator.

FIG. 2 is a front elevational view of the accessory for aerosol generator depicted in FIG. 1.

FIG. 3 is a rear elevational view of the accessory for aerosol generator depicted in FIG. 1.

FIG. 4 is a right side elevational view of the accessory for aerosol generator depicted in FIG. 1.

FIG. 5 is a left side elevational view of the accessory for aerosol generator depicted in FIG. 1.

FIG. 6 is a top plan view of the accessory for aerosol generator depicted in FIG. 1; and,

FIG. 7 is a bottom plan view of the accessory for aerosol generator depicted in FIG. 1.

The broken lines in the drawings illustrate portions of the accessory for aerosol generator that form no part of the claimed design.
